(57) **CLAIM**

We claim the ornamental design for an animal bedding, as shown and described.

DESCRIPTION

FIG. 1 is a top perspective view of a first embodiment of an animal bedding consisting of an upper and lower layer attached, showing our new design.

FIG. 2 is a front elevation view thereof.

FIG. 3 is a back elevation view thereof.

FIG. 4 is a right side view thereof.

FIG. 5 is a left side view thereof.

FIG. 6 is a top view thereof.

FIG. 7 is a bottom view thereof.

FIG. 8 is a top perspective view of a second embodiment of an animal bedding, consisting of an upper and lower layer attached, showing our new design.

FIG. 9 is a top perspective view of a third embodiment of an animal bedding, consisting of the top layer shown in FIG. 1, showing our new design.

FIG. 10 is a front elevation view thereof.

FIG. 11 is a back elevation view thereof.

FIG. 12 is a right side view thereof.

FIG. 13 is a left side view thereof.

FIG. 14 is a top view thereof.

FIG. 15 is a bottom view thereof.

FIG. 16 is a top perspective view of a fourth embodiment of an animal bedding, consisting of the lower layer shown in FIG. 1, showing our new design.

FIG. 17 is a front elevation view thereof.

FIG. 18 is a back elevation view thereof.

(Continued)

FIG. 19 is a right side view thereof.

FIG. 20 is a left side view thereof.

FIG. 21 is a top view thereof.

FIG. 22 is a bottom view thereof.

FIG. 23 is a top perspective view of a fifth embodiment of an animal bedding, consisting of an upper and lower layer attached, showing our new design.

FIG. 24 is a top perspective view of a sixth embodiment of an animal bedding consisting of the lower layer shown in FIG. 23.

FIG. 25 is a bottom perspective view of a seventh embodiment of an animal bedding, consisting of the upper layer shown in FIG. 23.

FIG. 26 is a top perspective view of an eighth embodiment of an animal bedding, consisting of an upper and lower layer attached, showing our new design.

FIG. 27 is a top perspective view of a ninth embodiment of an animal bedding, consisting of the lower layer shown in FIG. 26, showing our new design.

FIG. 28 is a bottom perspective view of a tenth embodiment of an animal bedding, consisting of the upper layer shown in FIG. 26, showing our new design.

FIG. 29 is a top perspective view of an eleventh embodiment of an animal bedding, consisting of an upper and lower layer attached, showing our new design.

FIG. 30 is a top perspective view of a twelfth embodiment of an animal bedding, consisting of the lower layer shown in FIG. 29, showing our new design; and,

FIG. 31 is a bottom perspective view of a thirteenth embodiment of an animal bedding, consisting of the upper layer shown in FIG. 29, showing our new design.

The broken lines in the figures illustrate portions of the animal bedding that form no part of the claimed design.
